UNITED STATES PATENT OFFICE.

WILLIAM McCALLUM, OF YONKERS, NEW YORK, ASSIGNOR TO THE BIGELOW CARPET COMPANY, OF CLINTON, MASSACHUSETTS.

DESIGN FOR A CARPET.

SPECIFICATION forming part of Design No. 14,612, dated February 5, 1884.

Application filed December 21, 1883. Term of patent 24 years.

To all whom it may concern:

Be it known that I, WILLIAM McCALLUM, of Yonkers, in the county of Westchester and State of New York, have invented and produced a new and original Design for a Carpet, of which the following is a full description, in connection with the accompanying photograph, which represents a face view of my new design for a carpet.

10 This invention relates to a new ornamentation of the face of a carpet, oil-cloth, or analogous fabric.

In the accompanying photograph are represented the various parts which enter into my new design.

15 A is a group consisting of a bunch of flowers, buds, leaves, and sprays.

B is a field containing leaves and flowers, surrounded by a border, a, which connects it 20 with fanciful corner-pieces b o d e.

C is a field containing leaves and flowers, and connected by a border, f, to fanciful corner-pieces g h i k.

D is a field containing flowers and surrounded by border l, having heart-shaped ornaments n.

m, r, and p are diamond-shaped ornaments placed between the figures and groups, the background of the carpet being speckled and covered with bunches and branches of flowers 30 and leaves, as shown.

I claim—

The design for a carpet, the same consisting of the figures A, B, C, D, a, b, o, d, e, f, g, h, i, k, l, n, m, r, and p, substantially as shown. 35
